METHOD OF MANUFACTURING METAL SHEETS OR STRIPS

Filed Jan. 5, 1927

UNITED STATES PATENT OFFICE

FREDRIK WILLE, OF WILMETTE, ILLINOIS, ASSIGNOR TO H. A. BRASSERT & COMPANY,
OF CHICAGO, ILLINOIS, A CORPORATION OF ILLINOIS

METHOD OF MANUFACTURING METAL SHEETS OR STRIPS

Application filed January 5, 1927. Serial No. 159,088.

My invention relates to the manufacture of sheets or strips made of steel or other metals by the rolling process. At the present time sheets are made on hand mills, the sheets being rolled out in singles, doubles or multiples according to the gauge and finishing required. Strip steel is generally rolled in continuous mills which have recently been developed to roll greater widths than was originally possible. The rolling of sheets by the continuous process is also being developed, the main problem, as in the case of wide strips, being to overcome the loss of too much heat in the rolling process, particularly when rolling the thinner gauges; there is also the mechanical difficulty of rolling a continuous wide strip or sheet in single thickness to the required gauge and finish. I have found it advisable in the manufacture of the thinner gauges including tin plate, not to attempt to finish the sheet and strip in one continuous rolling of single thickness, but to roll down as far as the heat of the metal will permit, and then double the sheet or strip for finishing, and have developed a convenient and efficient method of carrying out this operation.

My invention will be better understood by reference to the accompanying drawing in which—

30 Fig. 1 is a diagrammatic view illustrating the first step in my improved process which consists in bending the strip or sheet to be rolled into the form of a loop;

35 Fig. 2 is a similar view showing in full lines the beginning of the second step, which consists of flattening the loop, as indicated by the dotted lines in said figure; and

40 Fig. 3 is sectional detail view of a modified form of the sheet flattening means.

45 My improved process may be practiced by the use of any suitable apparatus, and as my present application is not concerned with the mechanism employed, I have shown only such parts of a simple apparatus as are necessary to a clear understanding of my improved process. Such process consists in first doubling the strip or sheet of metal that is to be rolled to a thinner gauge, this doubling being effected approximately midway between the ends of the strip or sheet so as to form a loop,

and bring the end portions of the strip in parallelism, or approximately so. The loop thus formed is then advanced through suitable flattening means to form a double strand. This cycle of operations may if desired be repeated several times, depending upon the gauge of the finished sheets desired. After the last doubling and flattening operation has been performed the material is re-heated and finished by rolling. The foregoing describes my improved process as I prefer to practice it, but in its broadest aspect it contemplates accomplishing the doubling operation by the use of two separate strips superimposed one upon the other without the formation of the loop referred to, and it should be understood that this mode of operation comes within the scope of the broader claims.

Referring now to the drawings, in connection with which I shall describe my improved process more specifically, 3 indicates a continuous metal strip, by which term I mean to include sheets of greater or less width, as well as narrow strips proper, which in practice may be of any desired length, in some cases as much as two or three hundred feet long. This strip is fed in the direction of the lower arrow in Fig. 1 over a roller table indicated by rollers 4 of any suitable number. These rollers are spaced apart and are arranged to be positively driven, preferably by an electric motor, in a counterclockwise direction as viewed in said figure. Said rollers lead to a set of pinch rolls 5, 6 which are also positively driven, the roll 5 turning in the opposite direction to the roll 6 which turns in the same direction as the rollers 4. From the pinch rolls 5, 6 the leading end of the strip passes between inner and outer U-shaped guides, the inner guide 7 being unitary and the outer guide being composed of two complementary hinged members 8, 9 curved to correspond with the curvature of the periphery of the guide 7 and spaced apart therefrom to provide a passage way 10 for the strip. In the illustrated construction the guide member 8 is hinged at 11 and the guide member 9 is hinged at 12, so that said guide members may be swung away from each other to the positions shown in Fig. 2. Stationary plates 13,

14 are provided adjacent to the hinges 11, 12, respectively, to aid in guiding the strip.

5 Adjacent to the upper marginal portion of the inner guide 7, and the plate 13, another set of pinch rolls 15, 16 is provided, beyond which is an upper roller table comprising rollers 17 similar to the rollers 4, and similarly driven except that provision is made for rotating the rollers 17 in either direction. 10 The same is true of the pinch rolls 15, 16. At the beginning of the operation the latter pinch rolls are driven oppositely to the corresponding pinch rolls of the lower set, and the rollers 17 are driven oppositely to the 15 rollers 4, so that the upper set of pinch rolls and the upper roller table serve to advance the leading end of the sheet in the direction indicated by the upper arrow in Fig. 1. Separate motors are preferably provided for 20 driving the upper and lower sets of feeding devices so that the upper set can be more conveniently reversed.

From the foregoing description it will be understood that when a sheet is fed into the 25 apparatus its leading end will move toward the looping guides over the rollers 4 of the lower table, and will be deflected by the curved inner faces of the guide members 8, 9, so that it will pass up over and around the 30 inner guide 7 and then be carried rearwardly between the pinch rolls 15, 16 over the rollers 17 of the upper table, thus forming a loop intermediate the ends of the strip.

It is of course desirable that the loop be 35 formed approximately midway of the length of the strip, although great exactness is not required because the last few feet of each end of the strip are usually discarded because of imperfections of various kinds.

40 It is desirable that as soon as a sufficient length of strip has been run through so that its upper and lower ends are equal, means be provided for automatically stopping the strip and then advancing it, looped end first, 45 between flattening rollers or equivalent devices, and in the illustrated construction I have indicated a series of switches by which such automatic stoppage may be effected. In the illustration switches 18, 19 are provided 50 in connection with the lower roller table, and switches 20, 21 in connection with the upper roller table. These switches may be in the form of pivoted bars, the several pivots being indicated at 22. The switches associated with each roller table are spaced apart, and the bars thereof are arranged to hang 55 pendent in position to intercept and be moved by the strip as it passes along. Normally such switches are in closed position, and they 60 are opened in sequence by the passage of the strip by them. Said switches are connected with the operating motors in such manner that when the strip has been doubled and its leading end carried back far enough so that 65 the loop portion 3^a is approximately midway

between the two ends of the strip the several rollers will be stopped, thereby arresting the strip. The guide members 8, 9 are then opened to the position shown in Fig. 2, and the lower rollers 4 and the lower pinch rolls 5, 6 are started again in the same direction as before, but the upper rollers 17 and the pinch rolls 15, 16 are started in a reverse direction, so that both the upper and lower end portions of the strip will be moved in the direction indicated by the arrows in Fig. 2, thereby 70 advancing the loop portion in the manner indicated by full lines in said figure. 75

The purpose of the latter movement of the looped strip is to carry its looped end into operative relation to flattening mechanism which in the illustrated construction is in the form of two swinging frames 23, 24 pivoted at 25, 26, respectively, to swing toward and from each other. The frames 23, 24 lie at 80 opposite sides of the path of the strip, their separated ends being toward the guide members 8, 9. Said frames carry sets of rollers 27, 28, respectively, driven preferably by separate motors, in a direction to advance the 85 doubled strip. When the strip is first advanced from the looping devices the frames 23, 24 are spread apart to receive the loop end of the strip, and are then closed against each other like a pair of scissors, as shown 90 by the dotted lines in Fig. 2. In thus closing they grab the strip, compress the doubled loop into a flat strip, and convey it forward through pinch rolls 30, 31 suitably supported at opposite sides of the path of the strip and 95 driven in any suitable way. These pinch rolls may feed the doubled strip directly into additional stands of rolls for further reduction or finishing, or may convey it directly into a heating or annealing furnace, 100 or to a shear for cutting into lengths for shipment, or for rolling into sheets or tin plate. The doubling operation may be repeated when rolling lighter gauges, as per usual practice, and in the drawings I have shown 105 rollers 4^a that may form part of a roller table adapted to conduct the strip for such further treatment as it may be desired to give it.

While I have shown one way of accomplishing the doubling, it can be performed in various other ways; for instance, if a short strip is used, the stops in the looping devices can be adjusted mechanically to stop the strip at an exact distance, without the over-travel incident to electrical control. Also, in place of the pivoted set of rollers for flattening the loop, two parallel elements with or without rollers, such as a curved box, or two flats 28^a (Fig. 3), straight or curved, 110 can be used for flattening the loop, the pinch rollers performing the duty of pushing and pulling the strip through. 115

It is also possible to move the strip continuously by opening the guides automatical- 120

ly as soon as the strip has traveled a certain part of the total distance on the return loop, so that the strip as a whole will move forward through the doubling guide while the return loop is still being formed. In this way a given length of strip may be run through continuously. If it is desirable to roll more than one length of strip continuously, the ends of several strips can be welded or otherwise fastened together.

Furthermore, as has been suggested, my improved method generically considered contemplates feeding two separate strips simultaneously out of a double superimposed strip mill onto roller tables such as those illustrated, the strips going through a doubling guide, which in that case will consist of a straight instead of a curved box, and in between flattening rollers which would then remain in closed position all the time.

After doubling, in case light gauges be desired, it may be found desirable to reheat and further roll, and redouble, forming four thicknesses, or in the case of tin plate, to redouble again, making eight thicknesses, which would take three doubling operations in succession, the "fours" or "eights" being finished in the usual finishing rollers. The method described is peculiarly applicable to the manufacture of tin plates from strip, but it may be used for any other purpose for which it is adapted.

What I claim as my invention and desire to secure by Letters Patent, is—

1. The method of doubling metal strips, consisting in moving the strip in one direction a predetermined distance, moving a portion of the strip in the opposite direction to that of its initial movement, thus forming the strip into a loop, and then advancing the loop between flattening means and in the direction in which the strip was first moved.

2. The method of doubling metal strips, consisting in moving the strip in one direction a predetermined distance, reversing the direction of travel of the leading end of the strip thus forming the strip into a loop, and then feeding the loop between flattening means and in the direction in which the strip was first moved.

3. The method of doubling metal strips, consisting in moving the strip in one direction a predetermined distance, reversing the direction of travel of the leading end of the strip thus forming the strip into a loop, and then feeding the loop between flattening means by the action of the loop forming means and in the direction in which the strip was first moved.

4. The method of doubling metal strips, consisting in moving the strip in one direction a predetermined distance, reversing the direction of travel of the leading end of the strip thus forming the strip into a loop comprising an upper run and a lower run, eject-

ing the loop by reversing the direction of travel of the upper run of the strip with the direction of travel of the lower run remaining unchanged, and then passing the loop as it is ejected through flattening means.

5. The method of doubling metal strips, consisting in moving the strip in one direction a predetermined distance, reversing the direction of travel of the leading end of the strip thus forming the strip into a loop comprising an upper run and a lower run, ejecting the loop by reversing the direction of travel of the upper run of the strip with the direction of travel of the lower run remaining continuous and unchanged, and then passing the strip as it is ejected through flattening means.
